UNITED STATES PATENT OFFICE.

GUSTAVUS L. STUEBNER, OF LONG ISLAND CITY, NEW YORK.

DESIGN FOR A DUMPING-BUCKET.

SPECIFICATION forming part of Design No. 20,906, dated June 30, 1891.

Application filed April 6, 1891. Serial No. 387,885. Term of patent 14 years.

To all whom it may concern:

Be it known that I, GUSTAVUS L. STUEBNER, a citizen of the United States, residing at Long Island City, in the county of Queens 5 and State of New York, have invented and produced a new and original Design for Dumping-Buckets, of which the following is a specification, reference being had to the accompanying drawings, forming part thereof, where-
10 in—

Figure 1 represents a perspective view of a bucket embodying my design, and Fig. 2 a side elevation thereof.

The principal feature of the design consists 15 in shaping the mouth of the bucket to impart thereto an essentially-rectangular outline, the

straight side and end lines at the mouth being curved where they are united, as illustrated at *a*. The lines *b* at the front side of the bucket extend diagonally from the mouth 20 inward to the bottom line *a'*, and the lines *b'* are straight, excepting at their lower end portion, which portion is inclined inward to meet the straight lines of the bottom, as shown at *b'*.
25

I claim—

The design for a dumping-bucket, substantially as herein shown and described.

GUSTAVUS L. STUEBNER.
